DESIGN FOR A SHOE

Evelyn Ziniti, New York, N. Y.

Application April 13, 1940, Serial No. 91,657

Term of patent 3½ years

To all whom it may concern:

Be it known that I, Evelyn Ziniti, a citizen of the United States of America, residing in city of New York, county of New York, and State of New York, have invented a new, original, and ornamental Design for a Shoe, of which the following is a specification, reference being had to the accompanying drawing, forming part thereof. The figure is a perspective view of a shoe showing my new design.

The design comprises a one-piece toe with an upturned fold coming over the flap on the vamp portion of the shoe, as shown.

I claim:

The ornamental design for a shoe, substantially as shown and described.

EVELYN ZINITI.
